UNITED STATES PATENT OFFICE.

CHARLES B. FAIRWEATHER, OF COATESVILLE, PENNSYLVANIA, ASSIGNOR
TO J. S. WORTH AND W. P. WORTH, OF COATESVILLE, PENNSYLVANIA.

DESIGN FOR A COVER-PLATE FOR BOILERS, &c.

SPECIFICATION forming part of Design No. 35,539, dated December 31, 1901.

Application filed November 30, 1901. Serial No. 84,270. Term of patent 14 years.

To all whom it may concern:

Be it known that I, CHARLES B. FAIRWEATHER, a citizen of the United States, and a resident of Coatesville, Pennsylvania, have 5 invented and produced a certain new and original Design for Cover-Plates for Boilers, &c., of which the following is a specification.

My design for a cover-plate for boilers, &c., is fully illustrated in the accompanying drawings, in which—

Figure 1 is a perspective view of the cover-plate. Fig. 2 is a longitudinal sectional view. Fig. 3 is a transverse sectional view on the line 3 3, Fig. 2. Fig. 4 is a transverse sectional view on the line 4 4, Fig. 2. Fig. 5 is a plan view.

The essential feature of the design is the oblong cover-plate, having a central portion separated from the flanged portion by an annular groove, the center portion having a 20 curved rib at the center separating the two plain surfaces.

A is the cover-plate, oval in shape and having an annular flange *a* and a central portion *a'*, separated from the flange by an annular 25 groove *a*². The central portion *a'* has two flat surfaces *b b*, perforated at *c c*, and these two surfaces are separated by a curved rib *d*, extending across the central portion *a*, as shown, producing the effect illustrated in the 30 drawings.

I claim—

The design for a cover-plate for boilers, &c., as herein described and as shown in the accompanying drawings. 35

In testimony whereof I have signed my name to this specification in the presence of two subscribing witnesses.

CHARLES B. FAIRWEATHER.

Witnesses:

WILL. A. BARR,
JOS. H. KLEIN.
